(57) **CLAIM**

The ornamental design for a combined chair and table set as shown and described.

DESCRIPTION

FIG. 1 is a front, right and top perspective view of the table component of the combined chair and table set of FIG. 17, shown separately to reveal aspects of the design that may not be apparent in other views.

FIG. 2 is a rear, left and bottom perspective view of the table component of the combined chair and table set of FIG. 17, shown separately to reveal aspects of the design that may not be apparent in other views.

FIG. 3 is a front elevation view of the table of FIG. 1.

FIG. 4 is a rear elevation view of the table of FIG. 1.

FIG. 5 is a left side elevation view of the table of FIG. 1.

FIG. 6 is a right side elevation view of the table of FIG. 1.

FIG. 7 is a top plan view of the table of FIG. 1.

FIG. 8 is a bottom plan view of the table of FIG. 1.

FIG. 9 is a front, right and top perspective view of the chair component of the combined chair and table set of FIG. 17, shown separately to reveal aspects of the design that may not be apparent in other views.

FIG. 10 is a rear, left and bottom perspective view of the chair component of the combined chair and table set of FIG. 17, shown separately to reveal aspects of the design that may not be apparent in other views.

FIG. 11 is a front elevation view of the sofa of FIG. 9.

FIG. 12 is a rear elevation view of the sofa of FIG. 9.

FIG. 13 is a left side elevation view of the sofa of FIG. 9.

FIG. 14 is a right side elevation view of the sofa of FIG. 9.

(Continued)

FIG. 15 is a top plan view of the sofa of FIG. 9.
 FIG. 16 is a bottom plan view of the sofa of FIG. 9; and,
 FIG. 17 is a front, right and top perspective view of a
 combined chair and table set showing my design.
 The broken lines depict portions of the combined chair and
 table set that form no part of the claimed design.

1 Claim, 17 Drawing Sheets
